UNITED STATES PATENT OFFICE.

ABIATHAR BLANCHARD, OF SOUTH NORWALK, CONNECTICUT, ADMINISTRATOR OF DEXTER DENNIS, DECEASED.

HAT.

SPECIFICATION forming part of Letters Patent No. 248,396, dated October 18, 1881.

Application filed April 30, 1881. (Model.)

To all whom it may concern:

Be it known that DEXTER DENNIS, of South Norwalk, in the county of Fairfield and State of Connecticut, invented a new and useful Improvement in Hats, of which the following is a specification.

Figure 1 is a perspective view of the improvement, shown as applied to a hat. Fig. 2 is a sectional side elevation of the same. 10 Similar letters of reference indicate corresponding parts.

The object of this invention is to increase the strength and durability of hats made of chip and other materials.

15 The invention consists in forming a sweat-band and brim-lining of waterproofed paper in one piece; also, in having the inner part of said lining and sweat-band cut in scalloped or toothed form; also, in gluing or otherwise cementing the said lining and sweat-band to the brim and body of the hat, as will be herein-after fully described.

A B represent a hat made of chip, straw, or other suitable material.

25 To the under side of the brim B of the hat is glued or otherwise cemented a lining, C, of waterproofed paper. The lining C is made in annular form, and its inner part is scalloped, toothed, or notched, and is bent up along, and 30 is glued or otherwise cemented to, the inner surface of the lower part of the body A of the hat, to serve as a sweat-band, D. The turned-up inner part, D, of the lining C can be further secured in place by the stitching that secures the band E to the hat-body A, as shown in Figs. 1 and 2.

The outer edge of the lining C is covered and is secured to the outer edge of the hat-brim B by a binding, F, of cloth or other suitable material folded around the said edges and

secured in place by stitching through its edges and through the said brim and lining.

With this construction the lining C and sweat-band D stiffen and strengthen the brim B and cover and protect the bend where the 45 brim B joins the body A. The lining C and sweat-band D, being waterproofed, are unaffected by sweat, and thus prevent the hat from being wet and injured by the sweating of the wearer. The lining C and sweat-band D, being made in one piece, have no folds or seams to be pressed against and hurt the head of the wearer.

Having thus fully described the invention, I claim as new and desire to secure by Letters 55 Patent—

1. A combined sweat-band and brim-lining for hats, made substantially as herein shown and described.

2. The combination, with the brim B and body A of a hat, of a combined lining and sweat-band, substantially as herein shown and described, whereby the hat is stiffened and strengthened, as set forth.

3. A combined lining and sweat-band, constructed, substantially as herein shown and described, in one piece, and with scalloped or toothed inner edge, as set forth.

3. The method of stiffening hats, substantially as herein shown and described, which 70 consists in cementing to the brim and body of the hat a combined lining and sweat-band, made in one piece, whereby the bend of the hat is protected, as set forth.

ABIATHAR BLANCHARD,
Administrator of estate of Dexter Dennis.
